ILLINOIS, ASSIGNORS TO STROMBERG MOTOR DEVICES COMPANY, OF CHICAGO,
ILLINOIS, A CORPORATION OF ILLINOIS.

MIXTURE CONTROL FOR AIRPLANE CARBURETORS.

Original application filed July 10, 1918, Serial No. 244,231. Divided and this application filed April 5, 1920. Serial No. 371,199.

Our invention relates to mixture control for airplane engines, and this application may be considered as covering a division of the subject matter disclosed in our application, Serial No. 244,231 filed July 10, 1918.

In the operation of airplanes, the changes in temperature and air density encountered as the altitude varies have made it imperative that the carburetor structure should be 10 adapted to meet these conditions, especially with regard to the delivery of fuel to the main discharge means. It has been found that as an ordinary carburetor is introduced into an area in which the air pressure is reduced, the mixture has a tendency to become enriched to an undesirable degree and extensive use of carburetors on air craft has proven that the proportion of air to fuel is reduced as the air density decreases. This is 15 due to the fact that as the pressure decreases, the air becomes rarer and the air content in the mixture decreases.

In accordance with our invention we provide means for controlling the fuel delivery 20 directly in proportion to the air, so that at all times the proper mixture may be produced. This we accomplish by connecting the fuel chamber with a region of suction in the carbureting chamber, so as to act upon 25 the fuel contained therein. By controlling the degree of suction applied to the fuel chamber the fuel delivered therefrom to the main discharge means may be regulated to a nicety.

The control of the degree or absence of the suction in the fuel chamber we accomplish by admitting air into the fuel chamber or 30 the suction connection between the carbureting chamber and the fuel chamber and by this means the suction effect may be neutralized entirely or to any degree. When the carburetor is in an atmosphere of normal or sea level pressure air is admitted to the suction line and as the airplane rises and the 35 air density decreases air will be excluded more or less from the suction line.

We provide for the automatic control of the air bleed by barometric control means and we also provide for manual control in 40 connection with such automatic control. Such manual control is necessary for many reasons. The barometric control means utilized are very delicate and subject to leakage

and such leakage would result in the mixture being very lean as the airplane approaches the ground, with possibility of serious danger unless the pilot be given some means for cutting off or modifying the action of the automatic means if the case should arise. A leaky or improperly operating barometric means would also result in the fuel consumption being unduly rapid in altitude flights. We have therefore devised a manual air controlling means by which the pilot may test, correct and adjust the mixture proportions whenever the automatic control is not functioning efficiently or properly, the manual means being controllable to cause air supply to the fuel chamber in addition to that supplied by the barometric control means or to cause reduction to any degree of the air supplied by the barometric controlled means.

Referring to the drawing Fig. 1, more or less diagrammatically illustrates a carburetor and barometric control means and manually controllable means associated therewith for regulating the air bleed into the suction line to the fuel chamber; Fig. 2, is an enlarged plan view of the manually controllable valve structure and Fig. 3, is an enlarged sectional view on plan 3—3 Fig. 1.

In the carburetor structure shown 10 designates the main barrel or mixing chamber which has a lateral extension forming the main air inlet 11, the inlet being preferably large to admit air freely and in large quantities when at altitudes at which the density of the air is decreased. A throttle valve 12 is mounted in the barrel 10 for controlling the flow of air into the engine. A double Venturi structure is shown comprising the large venturi 13 and the smaller venturi 14, the fuel supply nozzle 15 extending into the smaller venturi from the supporting boss 16 forming part of the carburetor framework. Fuel is delivered to the nozzle from the float chamber 17 by way of the passageway 18 and the calibrated orifice 19. The float 20 is of the conventional type and operates the valve 21 for controlling the inflow of fuel to the inlet 22 and thereby regulating the level of the fuel in the float chamber.

A suction passageway 23 communicates at 105 its outer end with the top of the float cham-

ber thru the restricted orifice 24, the inner end of this passageway communicating with the space 25 between the large venturi and the adjacent wall of the carbureting space 5 10, the ports 26 connecting the space 25 with the interior of the venturi at the throat of the venturi. When the carburetor is in operation suction effect from the engine is communicated through the ports 26 to the space 10 25 and from there to the passageway 23 to the top of the float chamber above the fuel therein. Such construction will tend to retard the flow of fuel from the float chamber to the main nozzle 15.

15 A threaded nipple 27 extends from the top of the float chamber frame and communicates with the suction passageway 23. A duct 28 connects with this nipple and extends to the manually controllable valve 20 structure designated as a whole M. This valve structure may be remote from the carburetor and is shown as secured to a supporting wall 29 which may be the instrument board on the airplane whose engine is 25 being served by the carburetor.

The barometric control device B may also be remote from the carburetor and as shown 30 may also be mounted on the wall 29. The barometric device is shown more or less diagrammatically. It comprises the barometric member or shell 30 shown in the form of an 35 expansible bellows which seats against the base 31 of the enclosing and protecting case or cage 32. A plate 33 is secured to the outer 40 end of the bellows and has the plunger extension 34 engaging in the cylindrical guide extension 35 on the base 31. A needle valve 36 extends axially in the plunger 34 and at its inner end has the head or washer 37 between which and the cover 32 of the frame 32 extends the spring 38 which resists the expansion of the barometric element 30.

45 The cover 32' has the extension 39 forming the valve chamber 40 into which the point of the needle valve extends for cooperation with the seat 41 to control the flow of air into the duct 42 which is adapted to be connected with the duct 28 thru the 50 valve structure M. Air enters the valve chamber 40 thru the inlets 43. The barometric element 30 is filled with dry air at sea level temperature and pressure and the valve controlled thereby is open when the 55 atmosphere surrounding the barometric element is of the same temperature and pressure. However, when the airplane rises and the atmospheric pressure decreases the barometric member will expand and move the 60 valve toward or into closing position.

Describing now the valve structure M, its frame comprises the base 44 and the top 45. The top has the valve chamber 46 with which connects the duct 28 leading to the 65 float chamber of the carburetor. Within the

valve chamber and seating on the base 44 is the plate 47 on top of which the valve disc 48 is rotatable. The rotational movement of the valve disc is guided by its hollow stem 49 which is journaled in the base 44. The cover 45 journals a shaft 50 to the outer end of which is secured the hand wheel 51. The inner end of the shaft has notches 52 for receiving the projections 53 on the valve disc so that this disc will turn with the shaft. A spring 54 enters into the hollow valve stem 49 and also into the recess 55 in the lower end of the shaft and this spring tends to hold the valve disc against its seat. A spring clip 56 frictionally engages the periphery of the hand wheel and serves to lock it in adjusted position.

15 A passageway 57 extends radially into the valve structure base 44 and connects with a port 58 thru the base and the valve seat plate 47. The air pipe 42 extends from the barometric controlling device B is connected with the passageway 57. The valve disc has the segmental port 59 for controlling the opening and closing of the port 58.

Extending in axial direction thru the valve structure base is the passageway 60 which, at its inner end, connects with the port 61 thru the seat plate 47 and, in the outer end of this passageway is secured the duct 62 which terminates in the air intake 11 of the carburetor structure. A circular port 63 in the valve disc controls the opening and closing of the port 61 as the valve is rotated. Stop lugs 64 and 65 on the frame 45 are engaged by the post 66 of the hand wheel to limit the rotational movement of the valve disc.

Describing now the operation, in the position shown on the drawing the passageways 57 and 60 are connected thru the valve ports with the valve chamber 46 so that the carburetor float chamber will receive its maximum supply of bleeding air, part of the air flow being from the barometrically controlled device by way of the duct 42, the valve structure, and the duct 28, and the balance of the air supply being from the carburetor air inlet by way of the duct 62, the valve structure, and the duct 28. By rotating the hand wheel and the valve disc in counterclockwise direction (Fig. 2) the connection of the air supply from the carburetor air inlet may be shut-off to any desired degree as the valve 63 moves away from the port 45. So long as the elongated or segmental valve port 59 connects with the port 58 air will flow through the float chamber from the barometric device. The counterclockwise rotation of the valve disc is stopped by the engagement of the post 66 with the stop lug 64, the end of the valve port 59 being at this time still in communication with the port 58. Thus while the automatic air supply is fully open the manual

controlled supply can be increased or diminished or entirely cut off, as desired. The automatic control of the air supply can thus be left entirely in full charge or this 5 air supply may be modified by the operation of the manual control.

When the valve disc is turned in clockwise direction from the position shown in the drawing the ports 58 and 61 will be 10 gradually closed and when the post 66 reaches the stop 65 the ports will be entirely closed and all air flow will be shut off from the float chamber. In advance of such 15 full closure of the ports they may be simultaneously opened or closed to any degree desired. If the stops 64 and 65 were removed the valve could be turned to shut off the automatic air supply and the air supply to the float chamber could be controlled entirely 20 manually.

The automatic mixture control is very useful in single pilot combat planes where the attention of the pilot is required on so many other things that he does not have 25 time to correct the mixture. It is impractical to attempt to set the automatic control to give the most economical mixture possible because this is too close to a condition where the engine might start to miss 30 fire if some of its elements are not functioning properly, and so the automatic control is given a margin of richness or a factor of safety. There are conditions, however, such as long flights over land and sea, where 35 the pilot is anxious to conserve his supply of fuel to the utmost and has time to adjust the mixture to the leanest possible point. It is very important that he should be able to do this without interfering with the setting 40 of the automatic control or its operation, and a manual control such as has been described is efficiently adapted for this purpose, the operator being able to manually adjust for the desired air bleed to the fuel 45 chamber.

Another situation quite often encountered is when the engine starts to miss fire in the

air which may be the result of the partial stoppage of the fuel jet of the carburetor, a sticking of the automatic control, or some 50 reason entirely separate from the fuel system. The pilot will, of course, wish to test so far as he can the various controls which he has, such as ignition switches, the gasoline fuel feed system, and the action of the 55 automatic control itself. Using the manual valve mechanism, the pilot can tell definitely whether the automatic control is at fault and the amount it is at fault, and can govern his course of action accordingly, 60 whether to land immediately or try to keep in the air, and so on. Thus there is a real practical advantage from the use of a manual control in co-operation with the automatic control. 65

We claim the following:—

In an altitude mixture control for airplane engines, in combination, a carburetor of the common type having a carbureting passageway and a constant level fuel chamber, a connection for communication of suction between the air space in said fuel chamber and a point of suction in said passageway, an air passageway leading from a region of atmospheric pressure to the air 75 space of said fuel chamber, a barometrically controlled valve for automatically controlling the supply of air through said passageway, and additional valve means associated with said air passageway, said additional valve means being controllable manually to supply air to the float chamber in addition to that supplied by said barometrically controlled valve and being 80 also controllable to reduce to any degree the 85 air supplied by said barometrically controlled valve.

In witness whereof, we hereunto subscribe our names this 2nd day of April, A. D. 1920.
